UNITED STATES PATENT OFFICE

2,331,480

BED STRUCTURE

Samuel Kroll and Nathan J. Kroll,
Chicago, Ill.

Application October 14, 1942, Serial No. 461,924

2 Claims.

(Cl. 5—247)

This invention relates to bed structures and more particularly to an improved spring and mattress for infants' cribs, which spring and mattress will be simple in construction, economical in manufacture and highly efficient in use.

It is an object of this invention to provide a spring and mattress assembly which will be highly flexible and which will readily yield to any load applied thereto.

Another object of this invention is to provide an improved spring structure by the use of a relatively inexpensive fibre panel which will freely yield to the thrusts of a body weight applied to the mattress.

Other objects and advantages will appear hereinafter.

The invention consists in the novel combination and arrangement of parts to be hereinafter described.

The invention will be best understood by reference to the accompanying drawing showing the preferred form of construction, and in which:

Fig. 1 is a fragmentary perspective view of a spring and mattress structure embodying our invention;

Fig. 2 is an exploded perspective view of the sub-structure of our new spring and mattress assembly;

Fig. 3 is a cross sectional detail view through the spring and mattress structure shown in Fig. 1 and at a slightly larger scale with respect thereto; and

Fig. 4 is a view similar to that of Fig. 3 with a load applied thereto.

As illustrated in the drawing, our improved bed structure 10 is a combined spring and mattress comprising a wooden frame 11 having parallel side rails 12 spaced from each other by end rails 13 to provide a rectangular frame adapted to be placed on a bedstead in the conventional manner. On the inner face of the side rails 12 there are formed a series of obliquely disposed grooves 14, and in each of these grooves is disposed an end portion of a wooden strip 15 which has a fibre structure having a high moment of elasticity to provide a leaf spring.

The spring arrangement of our new bed structure is completed by placing a baffle sheet 16 of relatively light cardboard or fibre over the top of the frame 11 with a portion of the marginal edges 17 of the baffle 16 overlying the top walls 18 of the rails 12 and 13. A plate 19 consisting preferably of a sheet of plywood has a film of glue 20 applied to its upper surface and the plate is pressed against the underside of the baffle

sheet 16 in the region of its mid section so that the plate 19 will adhere to the baffle 16.

The arrangement is such that the plate 19 provides a central sag eliminator for the baffle sheet 16 and also provides a bearing plate on the underside of the baffle sheet against which bearing plate 19 the free ends 21 of the wooden strips 15 bear to assist in supporting the center of the baffle sheet 16 in a horizontal position. The plate 19, further, provides a bearing surface 22 against which the free ends 21 of the strips 15 engage for smooth sliding action which is otherwise not satisfactorily provided by the loosely compiled fibres of the baffle sheet 16.

10 A layer of filler 23 of felt, hair or other suitable pad filler is then laid over the baffle sheet 16 and a covering 24 such as canvas, muslin or the like arranged over the baffle and filler with the sides 25 of covering 24 extending down and around the bottom of the frame 11 where the covering is fastened to the frame by means of upholsterer's tacks or any other well known means.

15 By this arrangement we have provided a combined spring and mattress structure which is assembled directly upon the frame structure 11 with the covering 24 and mattress filler 23 holding the baffle sheet 16 down upon the upper surface of the frame 11. Thus, the baffle sheet 16 is freely disposed on the frame 11 with no fastening means between the sheet 16 and frame rails 12—13 and by reason of this novel arrangement when a load is applied to the bed structure 10, as is shown in Fig. 4, the outer edges 17' of the sheet 20 16 are free to move upwardly, the inner corner 25 26 of the rails acting as a fulcrum for the deflecting action of the sheet 16.

25 While wooden leaf springs have been used in bed structures heretofore, the use of a floating baffle in conjunction with such spring structure has a novel advantage over known structures, the baffle being an integral spring unit in and of itself and being so arranged on the frame to provide a readily yieldable baffle throughout the entire 30 area of the bed.

35 While we have illustrated and described the preferred form of construction for carrying our invention into effect, this is capable of variation and modification without departing from the 40 spirit of the invention. We, therefore, do not wish to be limited to the precise details of construction set forth, but desire to avail ourselves of such variations and modifications as come 45 within the scope of the appended claims.

50 Having thus described our invention, what we

claim as new and desire to protect by Letters Patent is:

1. In a bed structure including a frame having leaf spring means extending therefrom to provide a resilient support at the mid region of said frame, a cardboard baffle sheet arranged on said frame, said baffle sheet having outer marginal edges loosely resting on said frame, a bearing plate adhered to the underside of said cardboard baffle sheet and engaging the leaf spring means, a covering for said baffle sheet and including means for securing said covering to said frame whereby to maintain said baffle sheet on said frame.
2. In a device of the class described including 15 a rectangular frame having leaf spring means extending inwardly therefrom to provide a resili-

ent support in the central area of said frame, the combination of a baffle sheet of relatively light pasteboard having marginal edges overlying said frame, a plate arranged on the underside of said baffle sheet and providing a bearing surface having engagement with said spring means, a covering arranged over said baffle sheet and extending downwardly and around said frame to maintain said baffle sheet in position relative to said frame, said baffle sheet being adapted to deflect in its central area with its marginal edges free to elevate with respect to said frame when a load is applied to said baffle sheet.
